UNITED STATES PATENT OFFICE.

JOHN H. BALMER, OF MAPLEWOOD, NEW JERSEY.

DESIGN FOR A TOWEL-BAR BRACKET.

Application filed July 9, 1928. Serial No. 27,419. Term of patent 14 years.

To all whom it may concern:

Be it known that I, JOHN H. BALMER, a citizen of the United States, and a resident of Maplewood, in the county of Essex and State of New Jersey, have invented a new, original, and ornamental Design for Towel-Bar Bracket, of which the following is a specification.

Reference is had to the accompanying drawing, forming part thereof, wherein

I claim:

The ornamental design for a towel bar bracket substantially as shown.

Signed at Newark in the county of Essex and State of New Jersey this sixth day of July, 1928.

JOHN H. BALMER.
